TOY SIMULATED TELEVISION SET, OR SIMILAR ARTICLE

John Mercorelli, 441 Summer Ave., Newark, N.J.

Filed Apr. 12, 1965, Ser. No. 84,713

Term of patent 14 years

(Cl. D34—15)

FIG. 1

FIG. 2

FIG. 3

FIG. 4

FIG. 5

FIG. 6

FIGURE 1 is a front elevational view of a toy simulated television set, or similar article, showing my new design;

FIGURE 2 is a rear elevational view thereof;

FIGURE 3 is a right side view thereof;

FIGURE 4 is a left side view thereof;

FIGURE 5 is a top plan view thereof; and

FIGURE 6 is a bottom view thereof.

The figure seen in broken lines in FIG. 1 is for illustrative purposes only.

I claim:

The ornamental design for a toy simulated television set, or similar article, as shown and described.
